UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT STOCK COMPANY OF FRANCE.

WHEELED GUN CARRIAGE HAVING DIVERGIBLE TRAILS.

Application filed November 27, 1922. Serial No. 603,699.

To all whom it may concern:

Be it known that I, EUGÈNE SCHNEIDER, a citizen of the Republic of France, residing at Paris, France, have invented new and 5 useful Improvements in or Relating to Wheeled Gun Carriages Having Divergible Trails, which is fully set forth in the following specification.

This invention relates to improvements in 10 the invention described in my copending application, Sr. No. 476,302, filed June 9, 1921.

The present invention is illustrated in detail in the accompanying drawings in 15 which:—

Figure 1 is a partial longitudinal sectional elevation.

Figures 2 and 2^a comprise a corresponding horizontal section.

20 Figures 3 and 3^a comprise an end elevation with partial cross-sections.

Figure 4 is a partial section taken along the line 4—4 of Figure 3.

25 Figure 5 is a partial section taken along the line 5—5 of Figure 2.

Figure 6 is a partial longitudinal sectional elevation of a modified construction of the elastic suspension of the gun, for transport.

30 The improved gun according to the present invention comprises in the known manner a wheeled axle, that is to say, an axle A with two wheels B. The carriage head proper C is fixed to the wheeled axle during 35 firing, but it can be suspended elastically from the said axle for transport, as is assumed to be the case in the example described in my aforesaid earlier patent.

35 The suspension may comprise leaf springs 40 D interposed between the axle A and the carriage head C. The carriage head C comprises for this purpose a block or buckle D¹ in which the bundle of leaf springs is fixed, the main leaf being connected by 45 means of knuckles D² to rings D³ attached to the wheeled axle A. The combination of the two trails F is capable of warping, in other terms, of assuming oblique positions relatively to the combined wheeled axle 50 B—A—B and the carriage head C. The said trails are pivoted at one end f to a cross-piece F¹, and each carries at its rear end an anchoring device (not shown).

55 The pivotal connection of the trails to the combined wheeled axle and carriage head is

effected in the manner described in my earlier patents, numbered 1085168 and more particularly 1084490.

This pivotal connection comprises a hollow longitudinal journal F² mounted in a bearing d¹ which is fixed to the block D¹, the latter being in its turn journalled in the carriage head C.

As hereinafter described, the combination d¹—D¹ is fixed to the carriage head C for 65 firing, in such a manner that the combined trails F—F¹—F can rock relatively to the combination C—d¹—D¹, in other words, relatively to the carriage head which is itself fixed to the axle tree A. This rocking movement of the trails F—F¹—F is effected by 70 rotation of the tubular journal F² in the bearing d¹.

As hereinabove described in my aforesaid earlier patent, the pivot pin g 75 of the gun pedestal G which carries the gun barrel, instead of having its foot-step bearing formed in the carriage head C, is located in a gun mount H which is pivoted to the carriage head C. This pivot pin g can 80 be returned at any time into the vertical position for which purpose it can receive both an uprighting or erecting a longitudinal uprighting movement on the one hand, and a transverse uprighting movement on 85 the other hand.

For the purpose of effecting the longitudinal uprighting movement the gun mount H is pivoted to the carriage head C by 90 means of a pivot pin I arranged vertically underneath the centre of gravity of the rocking mass and in front of the axle tree A. This pivot pin is mounted in an eye c of the carriage head (Figs. 1 and 3), and extends through two bearings h formed on 95 the gun mount H.

For the purpose of effecting the transverse uprighting movement of the pivot pin g, the combination constituted by the carriage head C, pivot pin I, gun mount H 100 and pedestal G, is arranged to pivot around the trunnion d². For this purpose the carriage head C has projecting laterally from it a helical toothed sector C² (Fig. 3) meshing with a worm J whose shaft is journalled 105 in a bearing A¹ fixed to the axle tree A.

A rigid connection between the carriage head and the axle tree A during firing is produced by the fact that the combination d¹—D¹ is fixed to the axle tree A by means 110

of a pin K (Figs. 2 and 3). On the other hand a rigid connection between the carriage head C and the hollow journal d^1 is produced by the meshing between the 5 toothed sector and the worm J carried by the axle tree A.

The rotation of the carriage head C around the journal d^1 for the purpose of effecting the transverse uprigting of the 10 pivot pin g is produced by means of a suitable gear for rotating the shaft of the worm J. This gear comprises for instance a bevel pinion j meshing with a pinion j^1 fixed on a shaft j^2 which is journalled in bearings 15 fixed to the axle tree and can be operated by means of a hand-wheel j^3 .

The mechanism for uprigting the pivot pin g in the longitudinal plane of the gun comprises, as shown in the drawings, a 20 toothed sector H^1 formed as a projection from the gun mount H, and meshing with a pinion L. The shaft of this pinion is journalled in a forked bearing block m formed on a journal M fixed to the carriage head C. 25 This journal M is co-axially mounted within the longitudinal tubular journal F² of the combined trails.

The transverse uprigting is effected by the pivotation of the combined trails around a geometrical axis of oscillation relatively to the combined wheeled axle and carriage head.

The mechanism for effecting the movement of the sector H^1 over the pinion L for 35 producing the longitudinal uprigting movement, comprises for instance, as shown in the drawings, a worm wheel L^1 fixed on the shaft of the pinion L, meshing with a worm L^2 which receives its motion from 40 the pinion L^3 meshing with a pinion L^4 whose shaft, which is journalled in bearings fixed to the block m, can be actuated by means of a hand wheel L^5 .

The gun elevating mechanism is fulcrumed 45 on the gun mount H. It comprises, on the gun pedestal G, two toothed sectors G^1 each meshing with a pinion s mounted on a shaft s^1 journalled in bearings fixed to the underside of the cradle S. The rolling of the 50 pinions s over the sectors G^1 is produced, for instance, by means of a transmission gear consisting of a worm wheel s^2 fixed on the shaft s^1 and meshing with a worm s^3 the shaft of which carries a pinion s^4 which 55 can revolve with the said shaft in a box s^5 fixed to one of the trunnions S^1 of the cradle S.

The pinion s^4 is driven by a pinion s^6 actuated by means of a hand wheel s^7 whose 60 geometrical axis coincides with the axis of the trunnion S^1 .

For training the gun, the gun pedestal G is engaged with the gun mount H which latter comprises a toothed sector H^2 formed 65 on an arc struck from a centre situated on

the axis of the pivot pin g. The movement of the gun pedestal over the sector H^2 is produced by means of a suitable transmission gear consisting, for instance of a worm N whose shaft n is journalled in bearings 70 fixed to the gun pedestal, and carries a bevel pinion n^1 which receives its motion through gearing $n^2-n^3-n^4$ actuated by means of a hand-wheel n^5 .

As hereinbefore described, the combination d^1-D^1 upon which the carriage head C is adapted to rock may, for the purpose of effecting the transverse uprigting movements, serve as a bearing block for a bundle of leaf springs D, the main leaf of which is 80 suspended from the wheeled axle A. This elastic suspension is rendered inoperative during firing, by the block D^1 being locked in position by means of the pin K, and also by the engagement between the sector C^2 and 85 the worm J.

In order to bring the elastic suspension into operation for transport, a means is provided for disconnecting the sector C^2 from the carriage head C, or more strictly speaking from an arm constituting a projection 90 from the latter.

As shown, the sector C^2 is connected to the said arm, by means of a pin O (Fig. 4).

If the two pins K and O be both withdrawn, the sector C^2 will remain rigidly connected to the axle tree A, and the arm projecting from the carriage head C will be capable of sliding over the said sector.

For the purpose of facilitating the mounting of the longitudinal axis of pivotatation of the combined trails relatively to the combined axle tree and carriage head, as well as the mounting of the elastic suspension, a recess is formed in the axle tree A (Fig. 1) for 100 the reception of a portion of the block D^1 together with the bundle of leaf springs carried by the latter.

In the modification illustrated in Fig. 6, the combination d^1-D^1 , around which the carriage head C can rock for effecting the transverse uprigting movements, is constructed in the form of a rocking beam to the ends of the arms of which there are articulated blocks D^4 , each carrying a bundle of 110 leaf springs D^5 the main leaf of which is suspended from the axle tree A.

This modification has the advantage of increasing the transverse stability of the gun during travel.

Having now particularly described and ascertained the nature of my said invention and in what manner the same is to be performed, I declare that what I claim is:

1. A wheeled gun carriage comprising, in combination, an axle, a block pivotally secured thereto having a longitudinally extending bearing portion, a pair of divergible trails adapted to rock about said portion, a carriage head pivotally secured to said portion 125

- tion, a mount pivotally secured to said head, a pedestal having a pivot pin, means pivotally securing said pedestal to said mount, and means for moving said pivot pin to a 5 vertical position from any inclined position.
2. A wheeled gun carriage comprising, in combination, an axle, a block pivotally secured thereto having a longitudinally extending bearing portion, a pair of divergible 10 trails adapted to rock about said portion, a carriage head pivotally secured to said portion and adapted to be rocked about the latter, a mount pivotally secured to said head, a pedestal having a pivot pin, means 15 pivotally securing said pedestal to said mount, and means for moving said pivot pin to a vertical position from any inclined position, the axis for the transverse uprighting of said pivot pin coinciding with the 20 longitudinal rocking axis of said trails, and the axis for the longitudinal uprighting of said pin being situated in front of said axle in a vertical plane passing through the center of gravity of the rocking mass.
- 25 3. A wheeled gun carriage comprising, in combination, an axle, a transverse member having a longitudinally extending bearing portion, a bundle of leaf springs interposed between said member and axle, a pair of 30 divergible trails adapted to rock about the longitudinal axis of said portion, a carriage head pivotally mounted on said portion, and means for moving said carriage in a vertical plane parallel to said axle about said portion.
- 35 4. A wheeled gun carriage comprising, in combination, an axle, a block having a longitudinally extending bearing portion, resilient means interposed between said axle and block for supporting the latter, a carriage pivotally mounted on said bearing portion for movement in a plane parallel to said axle, a pair of trails pivoted to said bearing portion and movable about the longitudinal axis of the latter, a gun mount, 40 a pivot pin interposed between said carriage and mount about which said mount may be moved in a plane at right angles to said axle, said pin being situated in a vertical plane passing through the center of gravity 45 of the rocking mass.
5. A wheeled gun carriage comprising, in combination, an axle, a block having a longitudinally extending bearing portion, resilient means for securing said block to 55 said axle, a carriage head pivotally secured to said bearing portion having a transversely extending arm, a toothed sector, a removable pin for securing said arm to said sector, means engaging said sector for rocking said carriage head about said bearing portion, said arm being adapted to slide along said sector when said pin is removed, and a pair of divergible trails pivotally secured to said bearing portion. 60
- 65 In testimony whereof I have signed this specification.

EUGÈNE SCHNEIDER.
